UNITED STATES PATENT OFFICE.

BENNARD HEMANN, OF ASHLAND, KENTUCKY.

METAL-PROCESSING MACHINE.

Application filed March 16, 1927. Serial No. 175,732.

My invention relates to a new and useful metal processing machine, and it relates more particularly to apparatus for closing the pores of the metal and for crystallizing 5 the face of metal, and also for scaling and polishing metal surfaces in general.

The object of my invention is a machine of simple and efficient construction for imparting to metal sheet, bars or other metal products, a rapid succession of blows or impacts whereby the surface as well as the interior 10 of the metal is subjected to a series of rapid compressions so as to make the metal as a whole more dense and also for producing a better surface upon the face of the metal.

With the above objects in view, my invention consists of a rotatable and substantially cylindrical anvil member or roll, mounted upon suitable journal supports and 20 guiding and feeding means, such as pairs of opposed and coacting guide rolls, suitably driven by power means, on either side of the anvil roll, adapted to feed a metal sheet, rod or bar in a continuous manner over the anvil 25 roll, thereby successively to position the successive areas of the metal upon the anvil roll.

My invention further consists of a rotatable hammer or impact device mounted above and in operative alignment with the anvil roll, having a series of independent and angularly spaced and pivotally mounted hammers or impact devices, adapted to contact with the metal positioned upon the anvil roll and to impart thereto the desired impacts or blows, means being provided to permit of an adjustment of the effective distance between the anvil and impact members.

For the purpose of illustrating my invention, I have shown in the accompanying drawings, forms thereof which are at present preferred by me since they will give in practice, satisfactory and reliable results, although it is to be understood that the various instrumentalities of which my invention consists can be variously arranged and organized and that my invention is not limited to the precise arrangement and organization of the instrumentalities as herein shown and described.

Referring to the drawings, in which like reference characters indicate like parts:

Figure 1 represents a side elevation partly

in section of a metal processing machine, embodying my invention.

Figure 2 represents a vertical longitudinal section taken on line 2—2 of Figure 1.

Figure 3 represents a vertical longitudinal section taken on line 3—3 of Figure 1.

Figure 4 represents an end elevational view of the hammer or impact roll.

Figure 5 represents a sectional view of the same taken on line 5—5 of Figure 2.

Figure 6 represents a perspective view of one of the series of dove-tailed pivot blocks forming part of the novel rotary impact device of my invention.

Figure 7 represents a perspective view of one of the series of dove-tailed spacing blocks.

Figure 8 represents a view in elevation of an impact hammer or hammer block of a modified construction.

In carrying out my invention I provide any suitable base 1, on which are mounted opposed pairs of upright, parallel frame members or standards 2 and 3, which may be suitably braced by the diagonal brace members 4. Between each two pairs of upright frame members or standards 2 and 3, suitable journal blocks 5 and 6 respectively are mounted, adapted rotatably to support the shaft or trunnions 7, carrying the horizontally disposed anvil roll 8.

Pairs of fore and aft bearing or journal housings 9 and 10 respectively are also provided, suitably mounted upon the base 1, and having their respective center lines extending parallel to the center line of the journal blocks 5 and 6. Each of the bearing housings 9 and 10 is provided with lower and aligned bearing openings or journal apertures 11 and upper journal blocks 12. The lower journal openings 11 support the lower shafts 13 and 14 respectively, which carry the lower feed and guide rolls 15 and 16 respectively. The upper journal blocks 12 are preferably mounted in direct vertical alignment with the bearing openings 11, and are also preferably movably or adjustably mounted in the bearing housings 9 and 10, so as to permit of the adjustment of the upper idle rolls 17 and 18 with respect to the corresponding lower or drive rolls 16 and 15. Thus each of the upper journal blocks 12 is slidably mounted in the upright channels 19, in the bearing housings

9 and 10, is suitably guided by a rod 20 and is maintained under a downward tension by a suitable spring 21, as shown particularly in Figures 1 and 3. Thus the idle rolls 17 5 and 18, carried by the corresponding shafts 22 and 23, respectively, are forced or pressed against the drive rolls 15 and 16, with a constant pressure by the springs 21, so as to accommodate materials of varying thicknesses.

The anvil roll 8 and the fore and aft drive rolls 15 and 16 are interconnected by means of a series of toothed wheels 24, 25 and 26, respectively, preferably of diameters directly proportional to the diameters of the corresponding rolls, and an endless link chain 27, extending around the three toothed wheels, and operatively engaging the same, so as to cause the three rolls to revolve in 15 the same direction at substantially the same peripheral speed.

Between the upright standard or frame members 2 and 3, a pair of opposed journal blocks 28 and 29 are adjustably mounted, 25 by any suitable means, such as the threaded supporting rods 30, threadedly anchored in the upper transverse yokes 31, and the opposed set screws 32.

By this means (Figures 1 and 2) the journal blocks 28 and 29 are supported in substantial vertical alignment with the corresponding lower journal blocks 5 and 6, and in a vertically adjustable manner, so as to permit of a variation of the distance between 30 the center line of the journal blocks 5 and 6 and the center line of the journal blocks 28 and 29. The journal blocks 28 and 29 support a shaft 33, upon which is fixedly mounted a hammer roll 34, having a series 40 of peripherally spaced and parallel longitudinal dove-tailed grooves 35 therein, which are adapted to receive a series of aligned and alternate pivot blocks 36 and spacing blocks 37 respectively. The pivot blocks 36 are provided with the pivot apertures 38 through which suitable pivot rods 39 may 45 be extended, which are in turn retained by any suitable means such as the cotter pins 40.

Suitable links 41 are pivotally mounted 50 upon the pivot rods 39, intermediate of each two pivot blocks 36, the free ends of said links 41, being similarly provided with pivot apertures and have pivotally secured thereto, suitable hammer blocks or impact members 42, carried by a series of pivot pins or a common pivot pin 43 extending through an entire row of links 41, held in place by any suitable means, such as the cotter pins 44. The hammer blocks or impact members 42, are thus adapted to oscillate about the upper pivot pins or rods 39. By revolving 60 the cylinder 34, the successive rows of hammer blocks 42 are brought into operative engagement to the sheet of metal 45 positioned upon the anvil roll 8. By suitably

adjusting the height of the journal blocks 28 and 29, with respect to the anvil roll 8, the intensity of the impact upon the metal sheet 45 may be suitably regulated.

In order to maintain the dove-tailed pivot 70 blocks 36 as well as the dove-tailed spacing blocks 37 in the dove-tailed channels of the roll 34, suitable terminal fastening means 46 may be employed, comprising a suitable wedge shape member adapted to engage the 75 outermost pivot block 36 in a manner shown particularly in Figures 2 and 4, being secured in place by suitable screws 47.

Each of the shafts 7 and 33 may be provided with fixed pulleys 48 and 49 respectively, or other suitable means adapted to receive a belt or the like, through which rotary motion may be imparted to said shaft 7 at the desired rate.

In Figure 8 I have shown a modified embodiment of my invention, to wit, a hammer block of an extended length, which may be pivoted directly upon the upper pivot rods 39, thereby eliminating the intermediate link 41.

It will thus be seen that by my invention I have devised a metal processing machine, adapted to be employed whenever it is desired to impart to a metal sheet or the like, a successive and uniform series of impacts either for the purpose of closing the pores on the surface of the metal or for solidifying the metal or for crystallizing the same. It will also be understood that in the specific illustration of my invention 100 shown in the drawings, the various operative elements of the same are shown partly diagrammatically and that my invention is not limited to the particular mechanical details therein shown.

It will now be apparent that I have devised a new and useful metal processing machine which embodies the features of advantage enumerated as desirable in the statement of the invention and the above description, and while I have in the present instance, shown and described preferred embodiments thereof, which are at present preferred by me since they will give in practice, satisfactory and reliable results, it is 110 to be understood that such embodiments are susceptible of modification in various particulars without departing from the spirit or scope of the invention or sacrificing any of its advantages.

Having thus described my invention, what I claim as new and desire to secure by Letters Patent is:

1. In a device of the character stated, an anvil roll, feeding rolls in operative alignment with said anvil roll, a hammer roll above and in operative alignment with said anvil roll, having a plurality of peripherally spaced longitudinal and inwardly enlarged channels, a series of pivot blocks 120

fixedly secured in said inwardly enlarged channels, and a corresponding series of hammer blocks pivotally supported by said pivot blocks in operative alignment with said anvil roll.

2. In a device of the character stated, an anvil roll, metal feeding rolls in operative alignment with said anvil roll, a hammer roll above and in operative alignment with said anvil roll, sets of aligned and peripherally spaced links pivotally secured to said hammer roll, and corresponding sets of hammer blocks pivotally carried by the free ends of said links, in operative alignment with said anvil roll, said hammer blocks being adapted to impact upon the metal carried by said anvil roll when said hammer roll is revolved.

3. In a device of the character stated, an anvil roll, feeding rolls in operative alignment with said anvil roll, a hammer roll above and in operative alignment with said anvil roll, having a plurality of peripherally spaced longitudinal and inwardly enlarged channels, a series of pivot blocks fixedly secured in said inwardly enlarged channels, a corresponding series of hammer blocks pivotally supported by said pivot blocks in operative alignment with said anvil roll, and means operatively interconnecting said anvil roll and said feed rolls to limit the rotary movement thereto to substantially the same peripheral speed.

4. In a device of the character stated, an anvil roll, feeding rolls in operative alignment with said anvil roll, a hammer roll above and in operative alignment with said anvil roll, sets of aligned and peripherally

spaced links pivotally secured to said hammer roll, corresponding sets of hammer blocks pivotally carried by the free ends of said links, in operative alignment with said anvil roll, and means operatively interconnecting said anvil roll and said feed rolls to limit the rotary movement thereof to substantially the same peripheral speed.

5. In a device of the character stated, an anvil roll, feeding rolls in operative alignment with said anvil roll, a hammer roll above and in operative alignment with said anvil roll, having a plurality of peripherally spaced longitudinal and inwardly enlarged channels, a series of pivot blocks fixedly secured in said inwardly enlarged channels, links pivotally secured to said pivot blocks and corresponding sets of hammer blocks pivotally carried by the free ends of said links, in operative alignment with said anvil roll.

6. In a device of the character stated, an anvil roll, feeding rolls in operative alignment with said anvil roll, a hammer roll above and in operative alignment with said anvil roll, having a plurality of peripherally spaced longitudinal and inwardly enlarged channels, a series of pivot blocks fixedly secured in said inwardly enlarged channels, links pivotally secured to said pivot blocks, corresponding sets of hammer blocks pivotally carried by the free ends of said links, in operative alignment with said anvil roll and means operatively interconnecting said anvil roll and said feed rolls to limit the rotary movement thereof to substantially the same peripheral speed.

BENNARD HEMANN.
